UNITED STATES PATENT OFFICE.

LIONEL H. LEADAM, OF NEW YORK, N. Y.

BOOT-TREE.

SPECIFICATION forming part of Letters Patent No. 621,424, dated March 21, 1899.

Application filed July 13, 1898. Serial No. 685,845. (No model.)

To all whom it may concern:

Be it known that I, LIONEL H. LEADAM, a citizen of the United States, residing at New York, in the county of New York and State 5 of New York, have invented new and useful Improvements in Trees for Boots and Shoes, of which the following is a specification.

My invention relates to trees for boots and shoes, and is designed more particularly as 10 an improvement on the tree forming the subject-matter of my application filed April 7, 1898, Serial No. 676,759.

The general object of my present invention is to provide a tree which while strong and 15 durable and reliable in operation is extremely cheap and simple and is therefore adapted to be sold with profit for a small price.

With this end in view the invention will be 20 fully understood from the following description and claims when taken in conjunction with the annexed drawings, in which—

Figure 1 is a section illustrating the manner in which my improved tree is placed in a shoe. Fig. 2 is a perspective view of the tree. 25 Fig. 3 is a transverse section taken in the plane indicated by the line 3 3 of Fig. 1, and Fig. 4 is a detail perspective view of a modification.

Referring by letter to said drawings, and 30 more particularly to Figs. 1 to 3 thereof, A is the toe or front member of my improved tree, which is preferably formed by a solid block of wood and is provided in its rear end with a kerf a. B is the heel or rear member, and C 35 is the intermediate member, which has for its purpose to adjustably connect the toe and heel members and to thrust the same in opposite directions, so as to properly stretch, flatten, and straighten the sole and shape the 40 upper of a shoe and fix the tree in the same.

In the preferred embodiment of my invention the heel member B is cast in the loop form shown and has the forward portions of its arms c arranged parallel and connected 45 by a pin d. The intermediate member C may be either cast or stamped from sheet metal, as desired. It has one end arranged in the kerf a of the toe member A and pivotally connected to said member and is provided with 50 a longitudinal slot e, closed at its opposite ends, and a plurality of notches f, the said

notches extending laterally from said slot and being slightly pitched forward, as shown, for a purpose presently described.

The pin d, connecting the arms of the heel 55 member B, rests in the slot e of the member C and permanently connects said members together. It is also designed to be seated in any one of the notches f, opening out of the slot e, to adjustably fix said members with 60 respect to each other and fit the tree to shoes of different sizes. By reason of the notches f being pitched forwardly, as stated, there is no liability of the pin d being casually displaced when the toe and heel members bear 65 against a shoe. Such slight pitch of the notches also serves to place the pressure or strain against the main portion of the member C rather than against the partitions intermediate of the notches f, which removes the 70 liability of said partitions being broken in operation.

In using the tree the heel member B and intermediate member C are held and used as 75 a handle for the convenient introduction of the toe member A to the forward portion of a shoe. The heel member is then swung down into the position shown in Fig. 1, after which the bar C is used as a lever, and its rear end is depressed until the pin d rests in 80 a dead-center, with the pin connecting the intermediate and toe members and the point at which the member B bears against the shoe. This will thrust the toe and heel members in 85 opposite directions in the shoe and will enable the tree to remove all wrinkles and straighten the sole and keep the shoe in perfect shape. To remove the tree when desired, it is simply necessary to raise the heel and intermediate members at the point of 90 flexure, when the tree may be readily withdrawn.

It will be appreciated from the foregoing that my improved tree is strong and durable, 95 is easily adjusted and efficient in construction, and is so simple and cheap as to admit of it being sold with profit for a small price, which is a desideratum.

In Fig. 4 I have illustrated a heel member b and a modified intermediate member C'. The heel member B is cast in the form shown— 100 that is to say, like the heel members in Figs.

1 and 2. It is shaped at its rear portion like the heel of a last, so as to have a broad bearing against the counter of a shoe, and has the forward portions of its arms arranged 5 parallel and connected by a pin d' . The intermediate member C' , like the member C before described, is preferably cast or stamped from sheet metal and has notches f' in one edge, the said notches being preferably 10 pitched for the purpose before pointed out. The heel member is held to the member C' by a pivoted strap g , which straddles said member C' , and the pin d' of the heel member is 15 designed to seat in the notches of the member C' after the manner shown. As will be readily observed by reference to Fig. 4, the strap g is of such a length as to permit of the pin d' being drawn out of a notch f' when it is desired to adjust the heel member with respect to the intermediate member.

The construction disclosed in Fig. 4 is operated in the same way as that shown in Figs. 1 to 3 and possesses the same advantages—viz, it is strong and durable and reliable in 25 operation and is also extremely simple and cheap.

While I prefer, as stated, to form the heel members of cast metal, I desire it understood that they might be stamped out of sheet metal 30 possessing sufficient rigidity for the purposes of my invention and bent into the shape desired.

Having thus described my invention, what I claim is—

35 1. The herein-described tree for boots and shoes comprising a toe or forward member, an intermediate member pivotally connected to the toe member and having notches at intervals in its length, and a heel member ad- 40 justably connected to the intermediate mem-

ber and having a pin arranged to seat in the notches thereof, substantially as specified.

2. The herein-described tree for boots and shoes comprising a toe or forward member, an intermediate member pivotally connected 45 to the toe member and having a longitudinal slot closed at its ends and lateral notches opening from said slot, and a heel member having a pin connecting it to the intermediate member; the said pin being adapted to be 50 moved in the slot and seated in the notches of the said intermediate member, substantially as specified.

3. The herein-described tree for boots and shoes comprising a toe or forward member, 55 an intermediate member formed by a strip of metal pivotally connected to the toe member and having a longitudinal slot closed at its ends and lateral notches opening from said slot, and a heel member of loop form having 60 its ends connected together and to the intermediate member by a transverse pin adapted to be moved in the slot and seated in the notches of the intermediate member, substantially as specified. 65

4. The tree described comprising a toe member, an intermediate member pivotally connected to the toe member and having notches at intervals in its length pitched upwardly toward its forward end, and a heel member ad- 70 justably connected to the intermediate member and having a pin arranged to seat in the notches thereof, substantially as specified.

In testimony whereof I have hereunto set my hand in presence of two subscribing witnesses. 75

LIONEL H. LEADAM.
